STATION INDICATOR

John W. Lee, Wilkes-Barre, Pa.

Application May 12, 1937, Serial No. 142,265

2 Claims. (Cl. 40—53)

This invention relates to station indicators and has for an object to provide a sign including a traveling web displaying the names of stations on subway cars, passenger cars, buses and other passenger carrying vehicles and having novel means for reversing the direction of travel of the web when the vehicle reaches the end of its route.

A further object is to provide an indicator which can be full automatic or hand controlled and the automatic controlling can be by closing of a door, photoelectric cell or other means of tripping the controlling switch.

A further object is to provide a station indicator of the type described having novel means for actuating the web to display the names of the stations successively, each station name being displayed prior to the arrival of the conveyance at the station.

20 A further object is to provide a device of this type which may be formed of a few strong simple and durable parts, which will be inexpensive to manufacture, and which will not easily get out of order.

25 With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming part of this specification,

35 Figure 1 is a front elevation of a station indicator constructed in accordance with the invention, with the housing removed to display the operating mechanism.

Figure 2 is a top plan view of the parts shown 40 in Figure 1.

Figure 3 is an end elevation looking toward the left end of the device.

Figure 4 is a detail longitudinal sectional view 45 of the reversing solenoid and crank shaft operated thereby.

Figure 5 is a detail cross sectional view taken on the line 5—5 of Figure 1, showing the shiftable clutch member of one of the clutches.

Figure 6 is a detail cross sectional view taken 50 on the line 6—6 of Figure 1 showing the shift ring and shift lever of one of the clutches.

Figure 7 is a longitudinal sectional view through one of the clutches and contiguous end portion of the associated web roller.

55 Figure 8 is a vertical sectional view taken on

the line 8—8 of Figure 1 with parts removed and showing the reversing switch controlled by the web.

Figure 9 is a detail side elevation of the timing switch controlled by movement of a friction roller riding upon the web above the upper web supporting roller.

Figure 10 is a diagrammatic view showing the electrical connections of the various switches, motor, motor controlling relays, reversing re- 10 lays, and reversing solenoid.

Figure 11 is a detail side elevation of a door operated switch for actuating the sign by movement of the door.

Figure 12 is a plan view of the web unrolled 15 and showing the reversing switch contact carried by the offset ends of the web.

For the purpose of clearness the housing for the station indicator is not shown but it will be understood that as usual in devices of this character the housing will have an opening in the front of sufficient magnitude to display the names of the stations one at a time.

Referring now to the drawings in which like characters of reference designate similar parts 25 in the various views, 10 and 11 designate superposed rollers upon which a web 12 is wound. The web is provided with legends 13 designating places on a route, for example.

Brackets 14 and 15 support the rollers at the 30 ends, one of the brackets being provided with pins 16 which enter notches 17 in the ends of the rollers to rotatably support the rollers. Each pin is spring pressed by a helical spring 18 which is concealed in a housing 19 and is sleeved upon 35 a stem 20 which extends exteriorly of the housing and is provided with a grip 21 by means of which the pin may be withdrawn to permit removal of the respective roller from the bracket 14.

The bracket 15, as best shown in Figures 1 and 7, is provided with bearings 22 which rotatably receive shafts 23 for driving both of the rollers. The end of each shaft is enlarged as shown at 24 and enters a recess 25 in the end 45 of the respective roller. Pins 26 project radially from the enlarged end 24 and are received in a groove 27 in the end of the roller to connect the shaft and the roller for rotation as a unit.

For rotating the rollers an electric motor 28 50 is mounted on the bracket 15 by bolts 29, or other connectors, as best shown in Figures 1 and 3.

The shaft of the motor is equipped with a worm 30 which meshes with a worm gear 31 fixed to an intermediate portion of a shaft 32 which is 55

5 journaled near the ends in bearings 33 that project outwardly from the bracket 15. The shaft is equipped at the ends with worm pinions 34 and 35 which mesh with worm gears 36 and 37 that are loose on the shafts of the rollers 10 and 11 respectively.

10 The driving gears 36 and 37 are clutched to the shafts of the roller by respective clutch members, best shown in Figures 1, 5 and 6. Each clutch member comprises a grooved shift pulley 38 which is splined on the shaft 23 of the respective roller and is provided with an annular series of resilient fingers 39 which are adapted to engage in grooves 40 formed in a frusto-conical hub 15 member 41 that is integral with the respective worm gear, as best shown in Figures 1 and 7.

15 The clutches are shifted alternately into clutching position to reverse the direction of travel of the web during the return journey of the conveyance on its route. For this purpose a shaft 42 is journaled in bearings 43 that are mounted on the bracket 15, as best shown in Figures 1 and 3. A shipper 44 is fixed to the shaft and is terminally equipped with forks 45 which enter 25 the grooves of the pulleys 38.

20 The shaft 42 is equipped with a crank 46, as best shown in Figure 4. The crank is terminally equipped with a projection 47 having an opening 48 of sufficient diameter to loosely receive a rod 30 49 which is equipped with collars 50 that alternately engage the head 47 when the rod is shifted endwise and swing the crank to turn the shaft 42 to which the shipper 44 is fixed.

25 The rod 49 is shifted endwise by a solenoid, 35 which as later will be explained is automatically controlled by switch devices carried by the web 12. The solenoid, as best shown in Figure 4, comprises two coils 51 and 52 disposed in alignment on a cylinder 53 having terminal flanges 40 one of which is fixed to the bracket 15 by screws 54 or other connectors. The core 55 of the solenoid carries the rod 49 and moves the same endwise in accordance with which one of the coils 51 or 52 is energized.

30 As shown in Figures 3 and 10, a switch 56 is closed by the operator of the vehicle to start the motor and pay off the web from one of the rollers and simultaneously wind up the web from the other roller. However, the closing of a door or 35 some other movement within the vehicle may be utilized to start the motor. The motor is automatically stopped after lapse of a sufficient time period to permit the legend designating the next stop to appear at the sight opening of the station indicator. For this purpose a roller 57 is mounted on bracket arms 58 that are hinged as shown at 59 to stationary pivot members 60. The bracket arms are of a sufficient length to dispose the roller 57 to ride upon the web as it 40 passes over the top of the upper roller 10, as best shown in Figure 3. The roller is driven by the web and when being driven it turns a cam disc 61 which is integral with one end of the roller. As best shown in Figure 9, the cam disc is provided with a pair of pivoted cam fingers 62 which, 45 during rotation of the disc, engage against respective stop pins 63 and are held thereby to project radially beyond the peripheral edge of the disc. The pins are so located that when the disc 50 is rotated in either direction one of the pins will hold its respective finger in operative position while the other pin will permit its respective finger to rock to inoperative position.

55 When in operative position the cam finger intercepts a leaf spring switch contact 64 and lifts

the contact out of engagement with a stationary switch member 65 thereby breaking the circuit to the motor through the motor controlling relay and stopping rotation of the web at the proper point to display the desired legend.

5 The direction of travel of the web is automatically reversed to present the legends in proper sequence during the return journey of the vehicle. To accomplish this switch contacts 66 and 67, of magnetic metal, are disposed on the web 10 adjacent to the ends thereof, as best shown in Figures 8 and 12. A permanent horseshoe magnet having legs 68, as best shown in Figure 2, is secured by a stationary clamp plate 69 in position to underlie the path of travel of the contacts 15 66 and 67. As best shown in Figure 8, a pair of aligned short switch contacts 70 and 71 are arranged upon an insulating strip 72 which is secured to the permanent magnet by bolts 73. Also, although not shown except diagrammatically in 20 Figure 10, a long switch contact 74 is disposed on the insulating strip parallel with and spaced from the switch contacts 70 and 71.

25 When the web is wound up upon the roller 10 the contact 66 will bridge the long contact 74 and short contact 70 and, being of magnetic metal, will be attracted by the permanent horseshoe magnet, to make a good electrical connection and close a circuit to a respective reversing relay 75, later described. Conversely when the web is wound up upon the roller 10 the switch contact 67 will bridge the long switch contact 74 and the short switch contact 71 and close a circuit to a respective reversing relay 76. These reversing relays merely select which one of the coils on the 30 reversing solenoid will be energized.

35 By referring now to Figure 10 it will be seen that a motor controlling relay 77 has one end of its coil connected to the trip switch 84 by a circuit wire 78 the other end of its coil being connected by a circuit wire 79 to the switch contact 65. The resilient switch contact 64 is connected by a wire 80 to one of the current supply wires 81 while the other current supply wire 82 is connected by a wire 83 to the trip switch 84 45 which is connected by a wire 85 to the time limit switch 56.

40 When the manually operated or automatic switch 84 is closed, a circuit may be traced through the wires just described to energize the coil of the motor relay and move the armature 86 of the relay against a pair of back contacts 87 one of which is connected by circuit wires 88 and 89 to the current supply wire 82. The other back contact is connected by circuit wires 5 and 6 to one 50 terminal of the motor 7 while the other terminal of the motor is connected by a circuit wire 8 to the current supply wire 81. Consequently when the motor relay coil is energized the motor circuit will be closed at the back contacts 87 through 60 the circuits just traced and the motor will start.

55 When the timing switch finger 62 opens the circuit through the relay coil by lifting the resilient contact 64 the motor relay coil will be de-energized and will break the motor circuit at the back contact 87 to stop rotation of the web at the proper place to display the desired legend.

60 The time limit switch 56 is a magnetically operated switch having a coil 90 one end of which is connected by a wire 91 to the supply wire 81 70 and the other end of which is connected by a wire 92 to the wire 6 of the motor circuit. When the motor circuit is open the magnetic time switch is open and keeps the motor circuit open and the motor circuit cannot be closed again after an op- 75

eration until the time limit switch closes anywhere from ten second to two minute intervals after each operation. The reason for this is that if the indicator is operated by the closing of a door and it is necessary to open the door again to let a passenger on or off, the indicator cannot be tripped within the time setting of the time limit switch.

To keep the relay 77 closed after the operator has removed his finger from the trip switch 84, there is a jumper connection 4 between the wire 78 and the armature 86 that energizes the coil on the relay 77 as soon as the motor circuit is closed at the back contacts 87.

15 The reversing relay 76 has one end of its coil connected by a circuit wire 93 to the short switch contact 71 on the horseshoe permanent magnet. The other end of its coil is connected by wires 94 and 95 to the before mentioned wire 89. The relay is provided with a pair of back contacts 96 one of which is connected by a circuit wire 97 to the coil 51 of the reversing solenoid. The other is connected to the wire 95.

When the switch contact 67 on the web bridges the long stationary contact 74 and the short stationary contact 71, the reversing relay 76 is energized to close a circuit at the back contacts 96 through the reversing solenoid coil 51 and reverse the direction of travel of the web as previously described.

To again reverse travel of the web when the vehicle resumes its outbound journey the contact 66 on the web will be in position to bridge the long contact 74 and short contact 70 of the horseshoe magnet and energize the reversing relay 75, which has back contacts 98 electrically connected in circuit with the coil 52 of the reversing solenoid. Consequently when the relay 75 is energized the coil 52 of the reversing solenoid will be energized 40 to reverse direction of travel of the web. The long contact 74 of the permanent horseshoe magnet is connected by a circuit wire 99 with the circuit wire 83 of the motor and through this long switch contact both of the short switch contacts 70 and 45 71 are supplied with current and selectively bridged by the web switch contacts 66 and 67.

In lieu of the manually operated switch 84 a conventional mercury switch 100, shown in Figure 11, may be operated by opening or closing 50 movement of the vehicle door 101 and to this end the switch may be carried on a centrally pivoted bracket arm 102 which is struck by a pin 103 to

tilt the mercury switch to circuit closing position as will be understood.

As shown best in Figure 8 a bulb 104 may be mounted in a suitable sprocket 105 that is attached to a stationary bracket 106 for illuminating the displayed legend.

Since the operation of the device has been described as the description of the parts progressed, it is thought that the invention will be fully understood without further explanation.

10

What is claimed is:

1. An electrically controlled station indicator comprising a web displaying the names of stations, rollers upon which the ends of the web are wound, brackets supporting the rollers, respective clutches connected to the rollers, a shipper for alternately clutching one clutch and de-clutching the other clutch, an electric motor geared to said clutches for driving the rollers, a circuit for the motor, a switch in said circuit, a relay controlling said circuit, means for holding the relay circuit closed when said switch is open, a timing roller frictionally engaging the web above one of the web supporting rollers and having yielding cam projections, a circuit in which the coil of 25 said relay is connected, a switch on the last named circuit opened by said cam projection to de-energize the relay and open the motor circuit when the web has advanced each station name into view after said manually operable switch is 30 closed, and a time limit switch in the motor circuit preventing closing of the motor circuit until lapse of a predetermined time period after each actuation.

2. An electrically operated station indicator 35 comprising superposed rollers, a web carried by the rollers and displaying station names, an electric motor, means connected to the motor for driving the rollers alternately, means including clutches on the rollers for de-clutching one roller 40 and simultaneously clutching the other roller to reverse the direction of travel of the web, a solenoid having two coils, a core for the solenoid connected to said reversing means, respective circuits for said coils, relays having back contacts 45 in said circuits, circuits including the coils of said relays, and switches in the last named circuits closed by the web selectively when at or near the end of its travel in either direction for energizing the relay coils selectively to selectively close the 50 circuits to the coils of said solenoid.

JOHN W. LEE.
